HEART VALVE

Denis Graham Melrose, London, England, assignor to
 National Research Development Corporation, London,
 England, a corporation of Great Britain

Filed Aug. 8, 1966, Ser. No. 3,380

Claims priority, application Great Britain Feb. 24, 1966

Term of patent 7 years

(Cl. D83—1)

Fig. 1.

Fig. 2.

Fig. 3.

Fig. 4.

FIG. 1 is a front view of a heart valve in an open position showing my new design;

FIG. 2 is a side view thereof;

FIG. 3 is a top plan view of the valve in a closed position; and

FIG. 4 is a perspective view of the heart valve in an open position.

I claim:

The ornamental design for a heart valve, substantially as shown.
